UNITED STATES PATENT OFFICE.

ADOLPH TISCHLER AND LOUIS B. TISCHLER, OF NEW YORK, N. Y.

SHEET-METAL MOLDING.

1,315,260.

Specification of Letters Patent. Patented Sept. 9, 1919.

Application filed July 11, 1919. Serial No. 310,044.

To all whom it may concern:

Be it known that we, ADOLPH TISCHLER, a citizen of the United States, and a resident of New York, borough of Bronx, in 5 the county of Bronx and State of New York, and LOUIS B. TISCHLER, a citizen of the United States, and a resident of New York, borough of Manhattan, in the county of New York and State of New York, have 10 jointly invented certain new and useful Improvements in Sheet-Metal Moldings, of which the following is a specification.

This invention relates to sheet metal moldings and particularly to such moldings as 15 have angular bends therein relatively to their length. The molding of the present invention is particularly adapted for forming the rim of the cover portion of a burial casket, and the object of our improvements 20 is to provide a molding of the character specified of simple construction and which is continuous around the four or more sides of the casket cover, and having only one joint, namely, where the two ends of the 25 molding are brought together. Further objects will appear hereinafter.

Referring to the drawing accompanying this specification, Figure 1 represents a strip 30 of sheet metal having notches or cuts or both in its lengthwise edges. Fig. 2 is a cross sectional view of the strip of Fig. 1 after that strip is folded into the requisite molding form. Fig. 3 is a perspective view showing 35 our improved molding folded transversely to form angular bends therein. Fig. 4 is a modification of what is shown in Fig. 1. Fig. 5 is a cross sectional view of the strip of Fig. 4 after that strip is folded into 40 the requisite molding form. Fig. 6 is a perspective view showing the molding of Fig. 5 folded transversely to form angular bends 45 therein. Fig. 7 is a perspective view of a corner cap, the use of which will appear later herein. All the figures of the drawing are to one scale except Fig. 7, which is to an enlarged scale.

Our improved molding is formed from a continuous strip of sheet material 2, preferably metal, having a notch 3, or a series 50 thereof, in one edge as 4. Said notches may vary in profile according to the form of the desired molding, and said notches penetrate said edge 4 to the upper boundary 8 of mid-portion 5. Said strip 2 is also provided in its 55 other edge 6 with one or more other notches or slits as 7. Said slits preferably penetrate

said edge at right angles and extend inwardly to the lower boundary of mid-portion 5. The width of said mid-portion 5 and of the edge portions having the notches and 60 slits therein may vary according to the requirements of the particular molding desired, and it will be understood that the moldings illustrated represent examples of the general class and which examples while 65 having certain essential characteristics in common may vary widely in proportion and appearance.

In some instances slit 7 is directly opposite notch 3, Fig. 1, and in other instances 70 slit 7 is offset lengthwise from notch 3, Fig. 4, and a second slit, 7^a, offset at an equal distance in the opposite direction from notch 3, is provided for purposes more fully explained later herein. After said notches 75 and slits have been cut into said strip at properly spaced positions for the particular molding and for the particular bends desired, said strip is bent along lengthwise parallel lines, as dotted lines 10, 11 and 12 80 of Figs. 1 and 4. Said bends form an inwardly extending molding face 13, Figs. 2, 3, 5 and 6, and in some instances a further slight bend is made along dotted line 8, Fig. 1, thereby providing a shelving side 85 14, Figs. 2 and 3. Said strip 2 is also bent along lengthwise parallel lines, as dotted lines 9, 15, 16 and 17, Figs. 1 and 4. These bends form an outwardly extending base 19, 90 preferably of approximately rectangular cross-section, Figs. 2 and 5. This hollow base may later be used for the reception of a stiffening rail 18. After said molding has 95 been formed into the desired profile as shown for instance in the cross-sections of Fig. 2 or Fig. 5, the mid-portion of said molding is bent transversely on a line connecting the root of notch 3 with the root of its opposite slit 7, Fig. 1, to conform to the showing of Fig. 3, or, said mid-portion is 100 bent along two oppositely oblique transverse lines, one connecting the root of notch 3 with slit 7 and the other connecting the root of notch 3 with the root of slit 7^a, Fig. 4, to conform to the showing of Fig. 6. In either 105 case said moldings are bent sufficiently to bring the opposite edges of said notch 3 into conjunction, thereby forming a continuous molding face 13. Said conjunctive edges may be secured together, as by solder, if said 110 sheet material is metal. This bending of the mid-portion 5 as described, necessarily opens

up spaces between the previously conjunctive ends of the segmental portions of base 19 and said openings may be conveniently covered by corner-caps as 20, Figs. 6 and 7, and which caps may be secured in place thereon by some convenient known means.

We claim:

1. A molding formed from a continuous strip of sheet material having a notch in

10 one edge thereof, said strip of material being bent along lengthwise parallel lines thereof crossing said notch, said bends forming a molding face, said molding being folded transversely at said notch position to bring the opposite edges of said notch into conjunction.

2. A molding formed from a continuous strip of material having a transverse slit in one edge thereof, said strip of material being bent along lengthwise parallel lines thereof crossing said slit, said bends forming an outwardly extending base of approximately rectangular cross-section, said molding being bent transversely at said slit to cause those portions of said base contiguous to said slit to form an open corner, and an angular cap of sheet material for covering said open corner.

3. A molding formed from a continuous strip of sheet material having a notch in one edge thereof and a transverse slit in the other edge thereof, said strip of material being bent along lengthwise parallel lines thereof crossing said notch, and bent along 35 other lengthwise parallel lines crossing said

slit, said first mentioned bends forming an inwardly extending molding face and said second mentioned bends forming an outwardly extending base of approximately rectangular cross-section, said molding being 40 bent transversely between said notch and slit to bring the opposite edges of said notch into conjunction and to cause those portions of said base contiguous to said slit to form an open corner.

4. A molding formed from a continuous strip of sheet material having a notch in one edge thereof and two transverse slits in the other edge thereof equally spaced from said notch, said strip of material being bent 50 along lengthwise parallel lines thereof crossing said notch and bent along other lengthwise parallel lines crossing said slits, said first mentioned bends forming an inwardly extending molding face and said second 55 mentioned bends forming an outwardly extending base of approximately rectangular cross-section, said molding being bent angularly transversely between said notch and one of said slits and between said notch and the other of said slits to bring the opposite edges of said notch into conjunction and to cause those portions of said base contiguous to said slits to form open corners respectively.

In witness whereof, we hereby affix our signatures this 9 day of July, 1919.

ADOLPH TISCHLER.
LOUIS B. TISCHLER.
